SEGMENTED NUMERIC DISPLAY PANEL

Richard A. Martel, Toledo, Ohio, assignor to
Owens-Illinois, Inc.

Filed Dec. 28, 1970, Ser. No. 26,649

Term of patent 14 years

Int. Cl. D14—02; D20—03
U.S. Cl. D26—5

FIG. 1

FIG. 2

FIG. 3

FIG. 4

FIG. 5

FIG. 1 is a front elevational view of a segmented numeric display panel showing my new design;

FIG. 2 is a rear elevational view thereof;

FIG. 3 is a top plan view thereof, the bottom being a mirror image of the top shown;

FIG. 4 is an elevational view taken from one side thereof; and

FIG. 5 is a front elevational view of a modified form of the segmented numeric display panel shown in FIG. 1, the modification resides in the slight angle of the vertical segments of the numerals.

I claim:

The ornamental design for a segmented numeric display panel, as shown and described.
